[57] CLAIM

The ornamental design for a body massage tool, as shown and described.

DESCRIPTION

FIG. 1 is a first end view of the body massage tool, showing my new design;

FIG. 2 is a second end view thereof;

FIG. 3 is a top view thereof;

FIG. 4 is a bottom view thereof;

FIG. 5 is a perspective view thereof; and,

FIG. 6 is a perspective view thereof in use condition, the broken line showing of the human body is for illustrative purposes only and forms no part of the claimed design.

FIG- 6
